VAPOR-ELECTRIC DEVICE

William E. Pakala, Forest Hills, and Henry C. Myers, Irwin, Pa., assignors to Westinghouse Electric Corporation, East Pittsburgh, Pa., a corporation of Pennsylvania

Application July 12, 1940, Serial No. 345,096

8 Claims. (Cl. 175—363)

1

Our invention relates to a vapor electric device, and particularly to a control system for a vapor electric converter of the make-alive type.

In the operation of make-alive type valves, it is necessary to periodically apply control impulses to the make-alive electrodes in order to initiate the current carrying arcs in the valves. Heretofore either auxiliary electronic valves or contact devices have been utilized for applying these periodic impulses. Heretofore control impulse supplying devices have been unsatisfactory either because of burning out of the control tubes or damage to the contact elements of the mechanical devices.

We have found that suitable control impulses can be generated by utilizing a saturable choke to distort the usual alternating current wave forms to produce suitable impulse wave forms for application to the control electrodes.

Further, by suitably impressing a premagnetizing current or biasing current on the saturable chokes, the phase relation or time instant of the application of the impulse can be controlled as well as the magnitude and wave form of the impulse.

We have found further that the total energy necessary to initiate the cathode spot may be decreased by the use of suitable energy storing devices in parallel with the initial control potential.

It is an object of our invention to provide a control system having saturable chokes to control the application of control potential to the make-alive electrodes of electric valves.

It is a further object of our invention to provide a control system in which the phase relation of the control impulse may be readily adjusted.

It is a still further object of our invention to provide a control system requiring a minimum amount of control energy.

Other objects and advantages of our invention will be apparent from the following detailed description taken in conjunction with the accompanying drawings, in which:

Figure 1 is a schematic illustration of a control system according to our invention,

Fig. 2 is a diagrammatic illustration of the current and flux variations in the saturable choke according to our invention.

Fig. 3 is a diagrammatic illustration showing the wave forms of current, voltage and flux in the saturable choke.

Fig. 4 is a schematic illustration similar to Fig. 1, showing a modification according to our invention, and

2

Fig. 5 is a schematic illustration showing a simplified construction according to our invention.

In the illustrated embodiment of our invention according to Fig. 1, an alternating current circuit 1 is connected to a direct current circuit 2 by means of a suitable transformer 3, current flow through the transformer 3 being controlled by means of a vapor-electric valve-device comprising a plurality of valves 4 of the make-alive type. Each valve 4 comprises a suitable evacuated container 5 having a vaporizable cathode 6, preferably of mercury or other suitable material. Co-operating with the cathode 6 is a suitable anode 7 which may be provided with a suitable shield 8. A make-alive electrode 9 is provided in contact with the cathode 6 and is preferably provided with an adjustable mounting 10 to determine the immersion of the make-alive electrode 9 in the cathode material.

Control impulses are obtained from any suitable source of alternating voltage of the same frequency as the main alternating-current circuit 1 of the vapor-electric valves 4, and having a predetermined phase with respect to said main alternating-current circuit 1. Said control-circuit alternating current source is herein illustrated as a control transformer 11 connected to the alternating current circuit 1. The secondary 12 of the control transformer 11 is provided with a plurality of phase windings, all of which have a common connection 13 which is connected by means of a suitable circuit 14 to the cathodes 6 of all of the make-alive type valves 4. The phase terminals are individually connected to the several make-alive electrodes 9 and in each of these connections we have provided a suitable non-linear impedance-device, illustrated in the form of a saturable reactor, choke-coil, or inductance-device, having a winding 15 associated with a magnetic core 16, preferably of a high permeability material having a sharp saturation point. While any suitable magnetic material may be utilized, we prefer to utilize a nickel-iron alloy such as disclosed in Yensen Patent No. 1,807,021.

Connected in series between the phase terminal and the make-alive electrode 9 is a suitable unidirectional conductor or asymmetrically conducting device 17 which may be either a copper oxide rectifier, a glow tube or any other suitable device. The series rectifier 17 is utilized to prevent inverse currents from flowing to the make-alive electrode 9 which might damage the make-alive device or even cause improper operation during the inverse half cycle. A suitable unidirectional or asymmetrically conducting device 18 is then

placed in shunt across the make-alive electrode 9 and the unidirectional conductor 17 to dissipate the inverse energy to prevent the cumulative unidirectional saturation of the magnetic core of the control transformer 11 which would occur if the positive and negative current-impulses were unequal, and also to prevent damage to the secondary phase-windings 12 of the control-transformer 11.

In order to control the shape of the current wave passing through the saturable choke 15, we have provided each of these chokes with a separate auxiliary direct-current winding 20 which is energized from any suitable direct current source herein illustrated as a direct current generator 21. Preferably, suitable resistance devices 22 are provided for permitting adjustment of the direct current in the auxiliary winding 20.

In series with the auxiliary winding 20 we have provided large capacity chokes 23 to damp out of the direct current circuit any surges arising in the alternating current circuit.

Because of the high permeability characteristic of the core 16 of the saturable choke, it is desirable to maintain a premagnetization of the core so that when the current is flowing to the make-alive electrode, the current plus the permagnetization will saturate the saturable core 16 so that a current impulse of considerable magnitude will flow through the saturable choke, while during the inverse potential the magnetizing current will not be sufficient to saturate the choke so that the inverse current will be kept at a minimum.

In the operation of the device of Fig. 1 according to our invention, the control transformer 11 supplies a substantially symmetrical alternating voltage of equal positive and negative half-waves, that is, having substantially no direct-current component, and having a substantially sinusoidal wave form 25 (Fig. 3) which produces a magnetizing current 26, establishing a flux 27 in the saturable reactor. At the same time the direct current premagnetization establishes a permanent bias flux A (Fig. 2) in the saturable core, and the size of the core is such that, as the alternating-current component of the flux increases, at an intermediate portion of each positive and negative half-wave of the alternating-current wave the total flux reaches the saturation point B, whereby a discontinuity in the saturation-curve of the induction-device is obtained at said portion of each positive and negative half-wave or impulse, so that the magnetizing current increases at a rapid rate, producing a peaked current-impulse of considerably less than half-cycle duration. This high current impulse is transmitted to the make-alive electrode 9 by the series connected unidirectional conductor 17. In the inverse half cycle, however, the current is not sufficient to overcome the premagnetizing effect sufficient to reach the saturation point so that the inverse current never exceeds the normal magnetizing current C of the choke. This inverse current is bypassed around the make-alive electrode 9 by means of the unidirectional conductor 18. By adjusting the amount of premagnetization the additional flux required to produce saturation can be changed and thus the phase relation of the impulse can be shifted as well as the time duration of the impulse.

For purposes of illustration, in Fig. 1, we have shown individual adjustments 22 for each of the premagnetizing windings 20. However, it is apparent that in normal operation all of these premagnetizing windings 20 will be connected to-

gether and controlled by a single adjustment 22, as shown in Fig. 4.

The embodiment according to Fig. 4 differs from that of Fig. 1 in that suitable energy storing devices herein illustrated as capacitors 30 are connected in parallel with the phase windings, and suitable impedances 31, herein shown as linear or non-saturating reactors, are utilized to control the rate of flow of current from the phase windings into the energy storing devices 30. At the instant when the magnetizing current produces a flux which exceeds the saturation point of the core, the energy storing devices will discharge, producing an impulses of steeper wave front and narrower angle than that secured without the aid of the energy storing devices. A steep wave-front of the impressed voltage-wave sending current through the reactor 15 and the make-alive electrode 9 is particularly useful, in the make-alive control of the rectifier-valves 4, because the condition of the make-alive electrode changes, from time to time, thus causing the magnetizing current of the serially connected reactor 15 to vary. If the wave-fronts of the successive half-cycles of this magnetizing-current are steep, the point at which ignition occurs will occur at very nearly the same time-phase in each half-cycle, regardless of the condition of the make-alive electrode, thus making the operation of the vapor-electric valves 4 more uniform.

In the modification according to Fig. 5, we have shown a simplified embodiment of our device which is particularly suitable to single-phase converters. However, a plurality of these devices connected to diametrically opposite phase terminals may be utilized for controlling polyphase systems. In order to simplify the construction the chokes of two diametrically opposite phases have been combined into a single three legged choke 16' which utilizes a single premagnetizing or phase shifting winding 20', thus conserving both material and space. As shown in Fig. 5, the alternating-current winding 15 of the saturable choke-coil or inductance-device is divided into two equal parts disposed on the two outer legs of the three-legged core 16', so that the alternating-current flux is circulated in a closed magnetic path of such dimensions as to be saturable under the operating conditions of the device, in the manner previously explained. The direct-current winding 20' is disposed on the central leg of the core 16', so that its flux divides between the two outer legs, so that the direct-current winding 20' is non-inductively related to the alternating-current windings 15 of the three-legged core 16'.

While for purposes of illustration, we have shown and described specific modifications according to our invention, it will be apparent that many changes and modifications can be made therein without departing from the true spirit of our invention or the scope of the appended claims. The broader aspects of the general combination using a saturable reactor in the make-alive control are covered by a companion-application, Serial No. 346,287, filed July 19, 1940, of William E. Pakala.

We claim as our invention:

1. A make-alive control-system, comprising a valve-device; an alternating-current source; a non-linear impedance; a linear impedance; a capacitor; a series asymmetrically conducting device; a shunting asymmetrically conducting device; a make-alive circuit including, in series-circuit relation, said alternating-current source, said linear impedance, said non-linear imped-

ance, said series asymmetrically conducting device, and a make-alive electrode of said valve-device, whereby unidirectional-current impulses of one polarity are delivered, through said series asymmetrically conducting device, to said make-alive electrode; a shunting circuit, including said shunting asymmetrically conducting device, connected in shunt-circuit relation around said make-alive electrode and said series asymmetrically conducting device, whereby a path is provided for unidirectional-current impulses of the other polarity; and a shunting circuit, including said capacitor, connected in shunt-circuit relation around both said alternating-current source and said linear impedance, so as to cooperate with said alternating-current source in supplying energy to said non-linear impedance and to said make-alive electrode and means for varying said non-linear impedance.

2. A make-alive control-system, comprising a valve-device; an alternating-current source; an inductance-device having a saturable core; a capacitor; an auxiliary impedance-device; a series asymmetrically conducting device; a shunting asymmetrically conducting device; circuit-means, serially including said alternating-current source and said auxiliary impedance-device, for impressing upon said capacitor an alternating voltage having substantially equal positive and negative impulses; circuit-means, including said capacitor, for impressing upon said inductance-device an alternating voltage having substantially equal positive and negative impulses, in such magnitude as to saturate the inductance-device at a portion of each of the positive and negative impulses, whereby a discontinuity in the saturation-curve of the inductance-device is obtained at said portion of each positive and negative impulse; make-alive circuit-means, including said series asymmetrically conducting device, for utilizing said inductance-device to cause peaked positive current-impulses to be supplied to a make-alive electrode of said valve-device; and a shunting circuit, including said shunting asymmetrically conducting device, connected in shunt-circuit relation around said make-alive electrode and said series asymmetrically conducting device, whereby a path is provided for the peaked negative current-impulses, an auxiliary winding on said inductance-device and variable means connected thereto for impressing direct current on said auxiliary winding.

3. A make-alive system comprising an alternating-current source; a saturable reactor; a capacitor; a series asymmetrically conducting device; a shunting asymmetrically conducting device; a current-supplying circuit including, in series-circuit relation, said alternating-current source, said saturable reactor, said series asymmetrically conducting device, and a load-device, whereby unidirectional-current impulses of one polarity are delivered, through said series asymmetrically conducting device, to said load-device; a shunting circuit, including said shunting asymmetrically conducting device, connected in shunt-circuit relation around said load-device and said series asymmetrically conducting device, whereby a path is provided for unidirectional-current impulses of the other polarity; and a shunting circuit, including said capacitor, connected in shunt-circuit relation around said alternating-current source, so as to cooperate with said alternating-current source in supplying energy to said saturable reactor and to said load-device, and means

for varying the saturation point of said saturable reactor.

4. A make-alive system comprising an alternating-current source; an inductance-device having a saturable core; a capacitor; a series asymmetrically conducting device; a shunting asymmetrically conducting device; circuit-means connecting said alternating-current source to said capacitor, for impressing upon said capacitor an alternating voltage having substantially equal positive and negative impulses; circuit-means, including said capacitor, for impressing upon said inductance-device an alternating voltage having substantially equal positive and negative impulses, in such magnitude as to saturate the inductance-device at a portion of each of the positive and negative impulses, whereby a discontinuity in the saturation-curve of the inductance-device is obtained at said portion of each positive and negative impulse; a current-supplying circuit-means, including said series asymmetrically conducting device connecting said inductance-device to a load-device; for utilizing said inductance-device to cause peaked positive current-impulses to be supplied to the load-device; and a shunting circuit, including said shunting asymmetrically conducting device, connected in shunt-circuit relation around said load-device and said series asymmetrically conducting device, whereby a path is provided for the peaked negative current-impulses, and means for varying the saturation point of said inductance-device.

5. In combination: an alternating-current source; an inductance-device including a three-legged magnetizable core having an outer-leg closed magnetic path of such dimensions as to be saturable under the operating conditions of the device, an alternating-current winding-means divided into two equal parts on said outer legs, and a substantially non-inductively related direct-current winding-means on the central leg of said core; a current-supplying circuit-means, including said alternating-current source and an alternating-current winding-means of said inductance-device, for supplying a load-device with a succession of controlled unidirectional peaked current-impulses of considerably less than half-cycle duration; and variable direct-current exciting-means for the direct-current winding-means of said impedance device.

6. In combination, an electric valve means having a control member, a source of alternating current, and an excitation circuit for transmitting an impulse of current to said control member comprising a capacitance, a saturable non-linear inductive reactance arranged to saturate within the normal range of operating current of said excitation circuit and connected to said capacitance for effecting discharge of said capacitance and a linear inductive reactance connected between said source and said capacitance and in the charging circuit of said capacitance for limiting the amount of current derived from said source upon discharge of said capacitance.

7. In combination, an electric valve means having a control member, a source of alternating current, and an excitation circuit for transmitting an impulse of current to said control member comprising a capacitance connected to be charged from said source, an impedance element, a saturable inductive reactance connected between said capacitance and said impedance element for abruptly discharging said capacitance

through said impedance element and a linear inductive reactance connected between said source and said capacitance for limiting the amount of current derived from said source when the inductive reactance of the saturable reactance abruptly decreases.

8. In combination, an alternating current supply circuit, a load circuit, a control circuit for transmitting an impulse of current to said load circuit comprising a capacitance, a saturable non-linear inductive reactance arranged to saturate within the normal range of operating current of said load circuit, means connecting said reactance and said load circuit in series and to said capacitance to establish a discharge circuit therefore, and means including a substantially linear inductive reactance connecting said capacitance with said source to provide a circuit for the transfer of alternating current energy from said source to said capacitance and to offer substantial impedance between said source and said capacitance during discharge of said capacitance.
